UNITED STATES PATENT OFFICE.

CHARLES R. WEAVER, OF BALTIMORE, MARYLAND, ASSIGNOR TO PETER C. HAINS, JR., UNITED STATES ARMY, OF NEW YORK, N. Y.

CONCRETE-MIXER.

No. 818,929.

Specification of Letters Patent.

Patented April 24, 1906.

Application filed November 25, 1905. Serial No. 289,000.

To all whom it may concern:

Be it known that I, CHARLES R. WEAVER, a citizen of the United States, residing at Baltimore, in the State of Maryland, have 5 invented certain new and useful Improvements in Concrete-Mixers, of which the following is a specification.

The invention to be hereinafter described relates to concrete mixing and handling apparatus whereby the constituent elements composing the mixture may be brought into proper relation and the product deposited in the desired location.

It is well known that concrete consists of 15 an intimate mixture of an active cementing substance and particles of inert material, which upon hardening of the cementing substance forms an artificial stone, the active cementing substance consisting usually of 20 hydraulic cement and water, forming a paste, and the inert material consisting of sand combined with broken stone or gravel, or both. To secure the best results and produce concrete of the desired character, it is 25 essential that each particle of the inert material shall be covered with a cement paste, the smaller particles serving to fill the interstices between the larger particles and the cement paste filling the remaining voids. In such 30 class of devices as herein referred to it is also desirable that the mixing apparatus may be so constructed or formed as to enable the material when mixed to be directly deposited in the required position without inter- 35 mediate transportation between the mixing apparatus and the place of deposit by a separate transporting means.

With these general considerations in view the object of the present invention is to provide 40 an apparatus whereby the required mixing of the inert materials and the active cementing substance may be secured in a simple, efficient, and economical manner, and, if desired, the product can be deposited in 45 place as required for use or taken from the apparatus and transported by suitable means to more remote locations.

Generally stated, the invention consists of 50 a plurality of hoppers or receptacles having bottom openings adapted to be placed one upon another or nested and means for connecting the hoppers so that they may be raised successively from their nested position to permit the materials to pass from one to

the other as the hoppers are successively raised.

The invention further consists of a preliminary mixing device which may be disposed within the top hopper of the series, automatically-operated doors for the hoppers, and in the parts and combinations to be hereinafter described, and definitely pointed out in the claims.

In the drawings, Figure 1 is a vertical sectional view of an apparatus embodying the 65 features of the present invention, said figure showing the several hoppers or receptacles in nested position one within the other. Fig. 2 is a side elevation and part sectional view of the same apparatus with the top hopper 70 raised from its nested position within the other hoppers and showing the material passing from the top hopper to the one next below, and Fig. 3 is a side elevation showing the series of hoppers raised successively 75 from their nested position and the material passing into the bottom hopper.

Referring to the drawings, which show one form or embodiment of the present invention, A A' A² A³ represent a series of hoppers 80 or receptacles of any desired or preferred form or number adapted to be nested together, as shown in Fig. 1; but preferably they are of general conical shape, and each has a bottom opening a, through which the 85 materials to be mixed may pass, as herein-after described.

The hopper or receptacle A, which for identification may be known as the "top hopper," is preferably provided with an upwardly- 90 extended flange or ring portion a' and may be reinforced by circular bands a², if desired. The top hopper A is provided with hooks or eyebolts b b, which may be of appropriate character and number to engage the hoisting- 95 slings b' b', connected to a hoisting link or hook b² of an appropriate derrick-lift, as b³. These parts may be formed of suitable character to support the weight not only of the top hopper and contained material placed 100 therein, but of all the hoppers, as will appear.

Attached to the top hopper A at suitable intervals are the eye-plates b⁴ b⁴, to which are secured the means for connecting the several hoppers. In the present form of the invention these eye-plates b⁴ b⁴ are shown as formed integral with the hooks or eyebolts b b and are provided with suitable openings through

which pass the connecting means $b^5 b^5$, which may be formed of wire ropes or cables knotted at their upper ends $b^6 b^6$.

The connecting means or ropes $b^5 b^5$ pass through suitable guides or eye-plates $b^7 b^7$, secured to the hoppers $A' A^2 A^3$, and are provided with stops $b^8 b^8$, so that as the hoppers are moved from their nested position, Fig. 1, to their elevated positions, Fig. 3, each hopper of the series will be successively raised from the one directly beneath, sufficient play or slack being provided between the stops $b^8 b^8$ to permit each hopper to be raised from the next lower hopper before said next lower hopper is raised from the one beneath it. The extent of such successive and independent movement will of course depend upon the distance between the stops $b^8 b^8$, which may be varied to suit the conditions of use, the essential in this respect being that each hopper be separately raised a sufficient distance from the one beneath to permit any material in it to pass through its bottom opening into the next hopper.

It is evident that the connecting means for permitting the hoppers to be joined in series and successively raised as described may be variously formed; but it has been found in practice that wire ropes having stops, as shown, are well suited to the conditions of use, as by their pliability they readily permit the hoppers to be nested together, as in Fig. 1, without danger of breakage or disturbance of the nested relation.

Each of the hoppers of the series is provided with a bottom closure or door C , hung upon arms c , pivoted at c' to suitable lugs c^3 , secured to the respective hoppers at opposite sides thereof, as shown in Figs. 2 and 3, so that such doors may be swung from their closing position to permit material to pass from one hopper to another beneath it.

In order that the doors C of the hoppers A , A' , and A^2 may be automatically operated as the said hoppers are successively raised from their nested position, Fig. 1, each of said doors of said hoppers is connected by an operating device C' to a hopper beneath it. This operating device may consist of a flexible connection secured at c^3 to one edge of the door or closure C and passed through suitable guide-eyes c^4 on the hopper, to which the door is hinged or pivoted, the end of said flexible connection being secured at a suitable point c^5 to a hopper beneath. From this construction it will be obvious that as one of said hoppers is raised from its nested position in the one beneath the operating device C' will gradually move the door or closure from the bottom opening and permit the material in the hopper to pass through. The time of thus opening the doors C may be varied, of course, to suit conditions of use by simply altering the length of the flexible connection C' .

It is to be here noted that the bottom clo-

sure or door of the bottom hopper A^3 is not provided with an automatic operating device, as are the other hoppers, which for identification may be generally termed the "upper" hoppers. This is to enable the material which has been passed into the bottom hopper A^3 to be retained in said hopper until wanted, at which time the entire series of hoppers may be raised and moved or swung by the usual derrick to enable the mixture to be deposited in place. To open the door C of the bottom hopper A^3 , a handle c^{10} , Fig. 3, is provided.

In order that the series of hoppers when in nested position may be properly supported without injury to the door of the bottom hopper, suitable supports $D D$ are provided, which may be of any desired character, but in the present illustration are shown as legs secured by rivets or bolts to the exterior wall of the bottom hopper.

From the construction thus far described it will be apparent that if the several hoppers be nested together, as in Fig. 1, and sustained upon their supports the materials to form the concrete or other mixture may be readily shoveled or dumped into the top hopper A . As a preferred manner of arranging the materials to form concrete the cement f , Fig. 1, is first placed in the top hopper. Then a layer of sand g of appropriate quantity is placed upon the cement, and upon this is placed the cracked stone or gravel h , water being then sprayed or dashed in suitable amount over the entire exposed surface. Such particular arrangement of materials, however, while desirable is not essential in all cases.

The top hopper A being now charged with the desired materials, the same is raised by means of the hoisting-slings $b' b'$, and as it rises from the hopper A' the door C is automatically opened by means of the operating device C' , thus permitting the material to pass from the top hopper into hopper A' . As the top hopper continues to rise the stops $b^8 b^8$ on the connecting means $b^5 b^5$ engage the eye-plates $b^7 b^7$ on hopper A' , whereupon said hopper starts to rise, and as it is thus lifted out of hopper A^2 the door C of hopper A' is automatically opened in a manner similar to the door of hopper A and the material passes to the next hopper A^2 beneath, which in turn is raised as the stops $b^8 b^8$ on the connecting means $b^5 b^5$ engage the eye-plates $b^7 b^7$ thereon, the door or hopper A^2 being operated automatically by the operating device as explained for hoppers A and A' . Thus by the successive raising of the several hoppers from their nested position by their connecting means the materials which are to form the mixture pass successively from one hopper to the other, becoming thoroughly mixed in the operation. The material is now in the bottom hopper, and the entire series of hoppers may now be moved or swung by a suit-

able derrick or other means to the place where the concrete is to be used, whereupon the door C of the bottom hopper can be opened by hand and the concrete deposited directly in place.

While it has been found that a device constructed as above described will produce a thorough mixture of the materials, it is desirable at times to provide for a preliminary mixing thereof prior to the passage of the materials from one hopper to another, and for this purpose the top hopper is provided with a preliminary mixing device. This device consists of an inclined body portion K, preferably in the form of a core and having an eyebolt k at its apex, to which is secured one end of a lifter k', the other end thereof being joined to the hoisting hook or link b² and of a length such that when the hoisting hook or link b² is raised to lift the hoppers successively from their nested position it will first raise the mixing device from its normal position at the bottom of the top hopper and dragging it through the materials indicated in Fig. 1 will cause a preliminary mixing thereof.

When the hoppers are in nested position, Fig. 1, the preliminary mixing device takes position over the bottom opening of the top hopper, and in order to center it properly it is provided with guides or wings k² k³ of any desired number, which striking upon the inside surface of the upper hopper as the mixing device is lowered therein insures the proper position of the device. These guides or wings k² likewise assist in the preliminary mixing of the materials as it is raised through the same prior to lifting the top hopper.

It is evident, of course, that the preliminary mixing device may be variously formed and constructed, the essentials in this respect being that it imparts to the materials in the top hopper a preliminary mixing prior to the discharge of such materials from the top hopper.

Reference has already been made to the action of the device as the hoppers are successively raised by their connecting means, and it now remains to direct attention to the nesting operation. Assume that the hoppers are in position indicated in Fig. 3 and the material discharged from the bottom hopper. The hoppers are then successively lowered, hopper A² approaching its nested position in hopper A³. The door of hopper A² first closes automatically as the operating device C' slackens, and then hopper A² seats itself in hopper A³, as indicated in Figs. 1 and 2. Hopper A' then approaches hopper A², its door C closing as the operating device C' slackens, and it finds a nested position, as indicated in Figs. 1 and 2, such operation being carried on throughout the series of hoppers.

As the top hopper is thus similarly seated in hopper A' the preliminary mixing device is

lowered by its lifter k' until the guides or wings k² rest upon the inside walls of the top hopper and correctly position the said device. The hoppers are now in nested position, as indicated in Fig. 1, and ready for another charge of materials and operation, as before.

It is evident that changes may be made in the details of connecting means for successively raising the hoppers and that other character of door-operating means may be found desirable; also, that the number of hoppers in the series may be varied and other changes made within the scope of the present invention.

Having thus described my invention, what I claim, and desire to secure by Letters Patent, is—

1. In a concrete mixing and handling apparatus, the combination of a plurality of hoppers having bottom openings and adapted to be nested one within the other, and means for connecting said hoppers in series to permit them to be successively raised from their nested position and cause the material to pass successively from one hopper to the other as they are raised.

2. In a concrete mixing and handling apparatus, the combination of a plurality of hoppers having bottom openings and adapted to be nested one within the other, a preliminary mixing device associated with one of said hoppers, and means for connecting said hoppers in series to permit them to be successively raised from their nested position and cause the material to pass successively from one hopper to the other as they are raised.

3. In a concrete mixing and handling apparatus, the combination of a plurality of hoppers having bottom openings and adapted to be nested within each other, a preliminary mixing device disposed within the top hopper, and means connecting said hoppers in series to permit them to be raised successively from their nested position and cause the material to pass successively from one to the other hopper of the series as they are raised.

4. In a concrete mixing and handling apparatus, the combination of a plurality of hoppers having bottom openings and adapted to be nested within each other, doors for closing said openings, means connecting said hoppers in series to permit them to be successively raised from their nested position, and devices associated with said hoppers for automatically opening the doors of the upper hoppers as they are successively raised from said nested position.

5. In a concrete mixing and handling apparatus, the combination of a plurality of hoppers having bottom openings and adapted to be nested within each other, doors for closing said openings, means for successively

raising the hoppers from their nested position, and devices associated with said hoppers for opening the doors to permit the material to pass from one hopper to the other.

5 6. In a concrete mixing and handling apparatus, the combination of a plurality of hoppers having bottom openings and adapted to be nested within each other, doors for closing said openings, a preliminary mixing 10 device disposed in the top hopper of the series, means for successively raising the hoppers from their nested position, and devices for opening the doors to permit the material to pass from one hopper to the other.

15 7. In a device of the character described, the combination of a plurality of hoppers having bottom openings and adapted to be nested within each other, a preliminary mixing device disposed in the top hopper, means 20 for connecting said hoppers in series to permit them to be successively raised from their nested position, and means for raising the preliminary mixing device in the top hopper.

8. The combination of a hopper, a preliminary mixing device disposed within said hopper, and having guides for centering said device in said hopper and means for raising the preliminary mixing device.

9. The combination of a hopper, having a 30 bottom opening, a door for closing said opening, means for opening said door, a preliminary mixing device disposed within said hopper, and having guides for centering said device in said hopper and means for raising the 35 preliminary mixing device.

10. A device of the character described comprising a plurality of hoppers having bottom openings, doors for closing said openings, means for connecting said hoppers in series to 40 permit them to be successively raised, and automatic devices connected to the doors of the upper hoppers for successively opening the doors of the upper hoppers as they are raised.

45 11. In a device of the character described, the combination of a plurality of hoppers having bottom openings and adapted to be nested in each other, hoisting-slings for lifting the top hopper, wire ropes connecting the 50 other hoppers of the series with the top hop-

per and stops arranged on said ropes for raising the hoppers successively, said stops being disposed a distance apart to permit an upper hopper to be raised from the one beneath it before the latter is raised.

55 12. In a device of the character described, the combination of a plurality of hoppers having bottom openings and adapted to be nested in each other, doors for closing said bottom openings, a flexible connection between the doors of each of the upper hoppers and the next lower hopper, guides through which said connections pass, and means for successively raising the hoppers from their nested position to cause the doors of the upper hoppers to be successively opened and permit material to pass through the bottom 60 openings of the upper hoppers.

65 13. In a device of the character described, the combination of a plurality of hoppers having bottom openings and adapted to be nested in each other, means for flexibly connecting said hoppers in series to permit them to be successively raised from their nested position and cause material to pass successively from one hopper to the other as they are raised, and supports for the bottom hopper to sustain the nested hoppers in position 70 to receive a charge of materials to be mixed.

75 14. In a device of the character described, the combination of a plurality of hoppers having bottom openings and adapted to be nested in each other, doors for closing said bottom openings, automatically-operating devices for opening said doors, means for 80 flexibly connecting said hoppers in series to permit them to be successively raised from their nested position and cause material to pass successively from one hopper to the other as they are raised and supports for the bottom hopper to sustain the nested hoppers in position 85 to receive a charge of materials to be mixed.

90 In testimony whereof I affix my signature in presence of two witnesses.
